Patented July 7, 1925.

UNITED STATES PATENT OFFICE.

JAMES FREDERICK MOSELEY, OF MANCHESTER, ENGLAND.

CLEANSING COMPOSITION.

No Drawing.

Application filed January 5, 1923. Serial No. 610,911.

To all whom it may concern:

Be it known that I, JAMES FREDERICK MOSELEY, subject of the King of Great Britain, residing in Manchester, in the county of Lancaster and Kingdom of England, have invented certain new and useful Improvements in or Relating to a Cleansing Composition, of which the following is a specification.

10 This invention relates to improved compositions of matter which may be generically termed "detergent compositions" and are capable of use as agents or assistants for washing, scouring, bleaching, dyeing and 15 similar operations. The invention particularly relates to compositions of the type containing saponaceous ingredients such as soap and a grease solvent. Various compositions of this general type have been described and 20 various emulsifying or stabilizing ingredients have been proposed to promote the stability of the emulsion.

It is an object of the present invention to provide improved compositions which exert 25 simultaneous bleaching, scouring and grease removing actions. A further object of the invention is to provide improved compositions in which the texture of a pasty composition is improved by certain mineral additions. Further objects of the invention are 30 to provide compositions containing certain named ingredients which have been found by practical experience to give satisfactory results on a large scale. The scope of the 35 invention will be defined in the appended claims. It may be noted that the term "detergent compositions" is to be considered as including solid or powdery masses in addition to the pasty or even fluid compositions 40 containing larger quantities of solvent. The term "solvents of high boiling point" will be applied to solvents having a boiling point substantially higher than 100° C. and typical examples of such high boiling solvents 45 are tetrahydronaphthalene, decahydronaphthalene, tetrahydro-β-naphthol and hexahydrophenol, and the term "high boiling solvents" is to be considered as including solvents whose boiling point is in the neighborhood 50 of the boiling points of the solvents above recited, since if solvents of a low boiling point are used, it is necessary to limit the temperature of the detergent operations.

The saponaceous ingredient preferably 55 consists of ordinary soap, but in addition to the alkali salts of fatty acids, I may also

use the alkali salts of sulphonated oils. These salts or the salts of sulphonated acids assist in emulsification.

The preferred grease solvents are the high boiling hydrogenated aromatic compounds and I have found by large scale experiments that compositions containing these bodies exert an improved bleaching action which is possibly due to hydrogen peroxide produced 65 by the oxidation of the hydrogen added during hydrogenation, but I shall describe my invention in such a way that it can be carried out irrespective of any theory as to the mechanism of the bleaching action. For 70 practical purposes, it is sufficient to state that I have discovered that these solvents do in fact exert this improved action.

In addition to the saponaceous ingredient and the solvent, I may add what may be 75 termed "texture-forming ingredients", i. e. mineral salts which improve the consistency of pasty compositions. The best example I have so far discovered of such mineral salts is borax. In British patent application No. 31078 of 1922, I have described the use of one specific natural silicate for the purpose of assisting emulsification, viz, bentonite, but I find that the soluble texture-forming mineral salts exert a different action and 80 borax in particular improves the homogeneity of the paste and allows a more transparent product to be made than is possible by the use of colloidal silicates.

The compositions containing the hydrogenated aromatic compounds of high boiling point are an important part of my invention. The invention further comprises compositions containing other known solvents for this purpose which have been stabilized 95 by the aid of my improved texture-forming ingredients. I may add that in practice I find that better results are obtained by employing a plurality of solvents and a plurality of stabilizing ingredients.

The following examples may be regarded as illustrative of the preparation of my improved compositions:—

Example 1.

30 parts fatty acid
25 parts decahydronaphthalene
25 parts tetrahydronaphthalene or tetrahydro-β-naphthol
1 part phenol or alcoholic body
1 part colloidal suspension of a silicate or a borate

10 parts water

8 parts sodium hydrate 70° Tw.

A trace of perfume

The several ingredients are thoroughly incorporated in a suitable mixing apparatus or mill.

Example 2.

30 parts hard soap

10 20 parts decahydronaphthalene

20 parts tetrahydronaphthalene

20 parts cyclohexanol

2½ parts chlorinated paraffin

3 parts butyl alcohol

15 4 parts water

½ part colloidal suspension of a silicate

½ part sodium borate

A trace of terpinol

The several ingredients are thoroughly mixed together by stirring during heating.

Examples of fatty acids, sulphonated oils and sulphonic acids which amongst others I may employ are respectively, stearic acid, sulphoricinoleic acid and sulphonaphthenic acid.

25

I declare that what I claim is:—

A detergents saponaceous composition containing soap, a hydrogenated aromatic compound of high boiling point and bentonite all emulsified together to form a semi-liquid 30 mass.

In witness whereof, I have hereunto signed my name this 16th day of December, 1922, in the presence of two subscribing witnesses.

JAMES FREDERICK MOSELEY.

Witnesses:

ERNAULD S. MOSELEY,

JOHN W. THOMAS.
